PRESSURE TREATING APPARATUS

Ernest L. Fickett, William O. Forman, and Philip E. Arthur, Fitchburg, Mass., assignors, by mesne assignments, to United Shoe Machinery Corporation, Boston, Mass., a corporation of New Jersey

Application June 1, 1933, Serial No. 673,804
Renewed September 22, 1937

16 Claims. (Cl. 91—46)

This invention relates to apparatus for treating absorbent materials with liquid under pressure of a degree sufficient to effect rapid impregnation of the material with the liquid employed for treatment. The invention is herein disclosed as embodied in an improved type of apparatus designed for tempering leather soles with water, but it is not limited either to the treatment of leather soles or to the use of water as the treating liquid.

In an earlier application for Letters Patent of the United States Serial No. 661,264, filed in our names March 17, 1933, we have disclosed and claimed certain improvements in apparatus for the same general purpose in which successive operations are brought about in a certain sequence under control of automatic electrical means, whereby a complete cycle of all the necessary operations may be accomplished without human intervention other than that required to supply the work to be treated and the act of pressing a button to initiate the cycle.

An object of the present invention is to provide an improved type of apparatus in which a desired sequence of operations will be brought about automatically without utilizing any electrical controlling means.

Another object is to provide an automatic apparatus of the type set forth in which the mechanical and hydraulic features are simpler and rendered more certain of operation.

As herein illustrated the present invention is embodied in an apparatus comprising a pressure-sustaining receptacle in which a treating liquid and the work to be treated thereby may be confined. For convenience of description, but not with any limiting intention, the treating liquid will be hereinafter referred to as water, since water alone is the liquid most commonly used to temper leather soles.

The treatment receptacle is provided with a removable closure to which closing and opening movements are imparted by an automatic mechanism including a hydraulic operating unit. The closure is provided with means by which it may be tightened against the receptacle and released therefrom, the tightening means being so combined with the hydraulic operating unit as to be operated thereby first to tighten the closure and thereafter to release it.

The apparatus also includes a source of water under pressure of a degree sufficient not only to operate the aforesaid hydraulic unit but also to effect rapid and thorough impregnation of the work with the water supplied to the receptacle.

Both the treatment receptacle and the hydraulic operating unit are supplied with water from this common source under control of valves that operate automatically to complete a cycle of operations in consequence of one manually imparted movement of a primary controlling valve by which the cycle is initiated.

Once the cycle has been initiated the following results are brought about automatically. The closure is moved to its operative position on the receptacle and maintained in pressure-sustaining relation thereto; water from the source of supply is pumped into the receptacle and the air initially in the receptacle is expelled through a vent in the closure; when all air has been expelled the vent is automatically closed by a float-valve the closing of which initiates the development of tempering pressure of the liquid in the receptacle; the tempering pressure continues for a predetermined length of time governed by an automatic timing device or, if preferred, it may continue only until a certain maximum degree of pressure is attained, whereupon the receptacle is cut off from the source of water supply, the pressure in the receptacle is relieved, the closure is released and retracted from the receptacle, and the timing device, if used, is restored to its initial position.

A feature of the invention consists in a novel and improved organization of elements comprising a valve movable manually to initiate a cycle of operations by directing liquid from the common source to the operating unit whereby the closure is carried to and clamped against the receptacle, and fluid controlled means thereafter operable automatically in consequence of closing movement of the closure to supply liquid from the common source into the receptacle, to maintain the pressure of the liquid in the receptacle for a certain length of time, to release the pressure in the receptacle, and to retract the closure.

Another novel feature consists in an improved combination comprising the closure, its operating unit and the timing device. These elements are so related that closing movement of the closure sets the timing device in operation and opening movement of the closure restores the timing device to its initial position.

Still another novel feature consists in an automatic pressure-operated valve that normally closes the conduit through which water from the source of supply is admitted to the treatment receptacle. This valve is arranged to be opened by the pressure of water by which the hydraulic

operating unit is operated to clamp the closure against the receptacle, but it does not open until the closure is clamped.

The various novel features and novel combinations of features constituting the invention are illustrated in the accompanying drawings and are hereinafter described and defined in the claims.

Referring to the drawings,

Fig. 1 is a vertical section of the apparatus partly broken away to conserve space, the closure of the treatment receptacle being shown as fastened to the receptacle which is to be regarded as full of water, although no water is represented;

Fig. 2 is a top-plan view of the receptacle and adjacent elements in the same condition as that represented in Fig. 1;

Fig. 3 is a vertical section of an automatic pressure-operated valve mechanism for controlling the draining of water from the treatment receptacle, the parts being in non-draining position as during a period of treatment;

Fig. 4 is an elevation of the entire apparatus, the closure being retracted but the primary controlling valve having been placed in the position that initiates a cycle of operations;

Fig. 5 is a vertical section of the treatment receptacle in a plane intersecting an overflow conduit;

Fig. 6 is a vertical section of the lower portion of a dash-pot that automatically controls the length of the pressure-tempering period, the position of the piston corresponding to a late stage of the pressure-tempering period as in Figs. 1 and 10;

Fig. 7 is a cross-section through the structure intersected by line 7-7 of Fig. 6;

Fig. 8 is a vertical section through the primary control valve and a fragment of the upper portion of the treatment receptacle, the valve being in the position that initiates a cycle of operations as represented in Fig. 4. The plane of this section is indicated by line 8-8 of Fig. 9;

Fig. 9 is a cross-section through the same valve mechanism but in a plane at right angles to that of Fig. 8 as represented by line 9-9 in Fig. 8;

Fig. 10 is an elevation of the same valve mechanism from the same point of view as that represented in Fig. 4 but corresponding to that stage of the cycle represented in Fig. 1, see line 10-10 of Fig. 8;

Fig. 11 is a vertical section through two check-valves in by-pass relation one of which admits water to the treatment receptacle, and the other of which releases water therefrom to relieve the pressure in the receptacle at the conclusion of the pressure-tempering period, the plane of the section being indicated by line 11-11 in Fig. 9;

Fig. 12 is an elevation corresponding to Fig. 10 except that it includes a pressure-operated device arranged to serve in lieu of a timing device, its effect being to terminate the pressure-tempering period as soon as the pressure in the treatment receptacle is developed to a predetermined degree;

Fig. 13 is a sectional view corresponding to Fig. 9 except that the primary controlling valve stands in its initial position as in the latter stages of a cycle after termination of a pressure-tempering period; and

Fig. 14 is a view corresponding to Fig. 10 except that it represents the primary controlling valve as having been returned to its initial position as in Fig. 13 in consequence of being released by the automatic timing device.

Referring to the drawings, and more particu-

larly to Figs. 1 and 4, the apparatus is mounted on a platform 1 supported by legs 2, 2 which provide a space for a motor 3 and a pump 5 both supported by the platform. The platform also supports a pressure-sustaining treatment receptacle 10 which may have, for example, a capacity for treating 100 soles at a time.

The receptacle 10 is preferably cylindrical and its upper end is formed to be closed and tightly sealed by a removable closure 12. As shown in Figs. 1, 2, 4 and 8 the closure is provided with four radially movable fastening members 14 for securing the closure to the receptacle in pressure-tight relationship. To cooperate with the fastening members 14, the receptacle is provided with an annular hub 15 having an internal flange 16. When the closure 12 is seated on the receptacle and the members 14 are projected under the flange 16 as shown in Figs. 1, 2 and 8 they operate with a wedging effect to increase the pressure of the closure against the receptacle, the wedging action being afforded by an inclined surface 17 on the flange 16 and by correspondingly inclined faces 18 formed on the fastening members. When the members 14 are retracted they and the closure 12 may pass freely through the space surrounded by the flange 16. To insure a pressure-tight joint between the receptacle and the closure, a compressible gasket 20 is arranged in a groove 21 in the hub of the receptacle. This gasket provides a seat for the margin of the closure.

To diametrically opposite bosses 22 are formed on the hub 15 and are bored to receive a pair of vertically extending rods 24 which serve to guide the closure to and from the receptacle. As shown in Fig. 1, shoulders formed on the rods 24 are seated on the upper faces of the bosses 22, and nuts 29 screwed on the lower ends of the rods serve to anchor the rods rigidly to the bosses. Brackets 25 (Figs. 1 and 2) affixed to the closure by bolts 26 are bored to provide bearing portions that surround the rods 24 and are adapted to slide thereon. The upper ends of the guide rods 24 (Fig. 1) are rigidly connected and braced by a yoke 30, one end of which, appearing at the right in Fig. 1, is provided with an extension 31 including a boss 32 through which a vertical hole is bored to guide the piston rod 35 of a timing device hereinafter described.

The yoke 30 also supports a double-acting hydraulic operating unit in coaxial relation to the receptacle 10. This operating unit not only carries the closure 12 to and from its operative position on the receptacle 10 but it also operates the radially movable fastening members 14. The operating unit comprises a hydraulic cylinder 33, a piston 35, and a piston-rod 36. The piston-rod extends through a gland 37 of a stuffing box in the cylinder head 38 affixed to the underside of the yoke 30. The upper end of the cylinder is closed by a head 39 having a port 40 for ingress and egress of water. The upper end of a pipe 101 (Fig. 4) is connected to this port. The heads 38 and 39 are connected by tie-rods 41 provided with clamping nuts 42. The lower end of the cylinder 33 is also provided with a port for ingress and egress of water that flows to and from through a pipe 125 (Fig. 4).

The lower end of the piston rod 36 is provided with a cylindrical toothed rack 80, the teeth of which are in mesh with four pinions 81, as shown in Figs. 1 and 2. The pinions are rotatably mounted on individual supporting pins 84 carried by a portion 85 formed on the closure 12. The

pinions are also in mesh respectively with rack-teeth 82 formed on the movable fastening members 14. The closure, the fastening members 14 and the hydraulic operating unit are so combined and organized that when the closure is supported in its retracted position by the operating unit as shown in Fig. 4, the fastening members 14 must be retracted toward the center of the closure, since the load comprising the closure and the fastening members is sustained by the intermeshing teeth of the pinions and the cylindrical rack 80. On the other hand, when the closure descends to its seat upon the receptacle 10, as shown in Fig. 1, the receptacle sustains the load and continued downward movement of the piston 35, due to hydraulic pressure on the upper side of the piston, causes the pinions 81 to project the fastening members 14 under the flange 16. The closure is then forced downward against the gasket 20 not only by the hydraulic pressure above the piston 35 but also by the wedging action of the members 14. This pressure-tight relationship of the closure and the receptacle is maintained throughout the pressure-tempering period, at the conclusion of which the hydraulic pressure in the cylinder 33 is transferred from the upper face of the piston 35 to the lower face, whereupon the piston rises. To pick up the load, the piston must first retract the fastening members 14, but when their retractive movement toward the center of the closure is arrested by abutting shoulders 87 and 88 (Fig. 2) they cause the rack 80 to pick up the load and carry the closure 12 to its initial position, as shown in Fig. 4.

Water for operating the piston 35 (Fig. 1) and for tempering the work may be obtained from a supply pipe 91 (Fig. 4) connected with any available source of supply, such as a street main. This pipe delivers the water into a small storage tank 90 and is provided with a manually operative shut-off valve 92. A float-valve (not shown) may be provided in the tank 90 to maintain the water at a suitable level therein. The tank 90 is included in a circuit comprising a pipe 93, the pump 5, a pipe 96, and a return branch 97 leading back into the tank 90 through a pressure-regulating valve 98. Thus, the pump 5, which operates continuously, will maintain pressure of the water in the pipes 96 and 97, and the water driven by the pump will circulate continuously through the regulating valve 98 except when it is directed elsewhere.

The pipe 96 also delivers water to the treatment receptacle 10 and to the cylinder 33 of the hydraulic operating unit under control of a primary controlling valve 115 (Figs. 8, 9 and 13). This valve is arranged to oscillate through an arc of 90° in a valve casing 100, and has a stem 120 that projects through packing 118 and is provided with an operating handle 102 secured by a key 121. The casing 100 has a supply port 122, two distributing ports 123 and 124, and a draining port 158. The valve 115 has two separate channels 116 and 117 the first of which is arranged to connect the supply port 122 alternatively with the distributing ports 123 and 124, while the channel 117 is arranged to connect the draining port 158 alternatively with the distributing ports.

The valve 115 is initially maintained in the position shown in Figs. 13 and 14 by a spring 146, one end of which is attached to an arm 145 forming a part of the handle 102. When the valve is in this position water under pressure from the

pump 5 may flow from the pipe 96 through the supply port 122 in the valve casing 100, through the channel 116 in the valve, and thence into the lower end of the cylinder 33 of the hydraulic operating unit through a distributing conduit including the port 124 and the pipe 125. The water is thus caused to raise the piston 35 and to maintain it at the upper end of the cylinder 33 while the attendant arranges a collection of soles for treatment. Moreover, while the valve 115 stands in its initial position it also provides for returning water from the upper portion of the cylinder 33 to the storage tank 90 through port 40 (Fig. 1), pipe 101 (Fig. 4), port 123 (Fig. 13), channel 117, port 158 in the casing 100 (Fig. 8), port 162, and return pipe 108 (Fig. 4).

When the work is ready for treatment, the attendant has merely to swing the handle 102 of the primary controlling valve to the position shown in Fig. 4 where it will be caught and maintained by a latching finger 140 (Fig. 10) formed on a lever 141 mounted on a pivot 142. This latching member is normally maintained in its latching position by a spring 143, the lever 141 being thereby maintained against a stop 144 while the latching finger 140 is maintained in a notch 139 formed in a stud 138 carried by and projecting from the handle 102 (Fig. 8). In this position the valve 115 releases the water from the lower end of the cylinder 33, supplies water from the pump to the upper end of the cylinder, and eventually supplies water from the pump to the interior of the treatment receptacle 10. This position of the valve 115 is shown also in Figs. 8 and 9. Now the water from the pump is directed into the upper end of the cylinder 33 through the following connections: pipe 96, supply port 122, channel 116 and distributing conduit comprising port 123, pipe 101, and port 40 (Fig. 1). The water now expelled from the lower end of the cylinder 33 is not discharged but returns to the storage tank 90 through the following connections: pipe 125 (Fig. 4), port 124 in the valve casing 100 (Fig. 9), channel 117, draining port 158, port 162, and return pipe 108.

While the piston 35 (Fig. 1) is descending to apply the closure 12 to the treatment receptacle 10, the cylinder 33 utilizes the hydraulic pressure developed by the pump, but when the piston reaches the lower limit of its travel the pressure of the water operating thereon increases sufficiently to open a normally closed check-valve through which some of this water may flow into the treatment receptacle. This check-valve is indicated at 130 in Figs. 9 and 11 and is located in a branch conduit that connects the receptacle with the distributing port 123. Since no more water can flow to the cylinder 33, the full pressure developed by the pump opens the valve 130 against the force of a closing spring 132, whereupon the water may flow through the branch conduit comprising the outlet 126 (Fig. 9), a pipe 103 (Figs. 3 and 4), a valve casing 105, a check-valve 154, and a pipe 106 that leads into the treatment receptacle.

The water flowing through the pipe 103 into the valve casing 105 operates against a flexible diaphragm 153, the purpose of which is to control the discharge of water from the treatment receptacle. As shown in Fig. 3, the diaphragm 153 is arranged to stop the flow of water through an outlet port at its right-hand side so long as the maximum available pressure of the water acts against its left-hand side, as when the primary controlling valve 115 remains in the position shown in Figs. 4 and 9. Thus, the water pres-

sure developed by the pump 5 will cause the receptacle 10 to be filled with water and will thereafter maintain tempering pressure of the water in the receptacle until the valve 115 is returned to its initial position.

On the other hand, when pressure against the left-hand side of the diaphragm 153 is relieved as hereinafter explained, the back pressure from the receptacle 10 will force the diaphragm 153 to the left, since the check-valve 154 will prevent such back pressure from acting on the left-hand face of the diaphragm. Consequently, the diaphragm will open communication between the pipe 106 and a discharge pipe 161 through which some of the water in the receptacle may flow. The discharge pipe 161 delivers the discharged water into an overflow or draining conduit 160 (Figs. 4 and 5) formed on the exterior of the receptacle 10. The water in the receptacle may therefore descend to the level at which the pipe 161 is connected to the overflow 160, this level being indicated by a horizontal broken line in Fig. 5.

Referring to Fig. 9, the check-valve 130 may be regulated to remain closed until any desired pressure has been developed in the port 123. For this purpose, the closing spring 132 surrounding the valve stem 136 may be compressed by a screw-threaded sleeve 133 to maintain various degrees of closing force. The sleeve 133 is screwed into an internal screw-thread 134 in the casing 100 and is provided with a bore 137 in its upper end in which the valve stem may play up and down. A screw-cap 135 screwed on the upper portion of the sleeve 133 may be screwed down to maintain the sleeve against accidental turning and to guard against leakage through the screw connection between the sleeve and the valve casing. A small port 129 forms a by-pass around the valve 130 to insure the maximum available water-pressure in the receptacle 10 during the pressure-tempering period, but this by-pass port is not of sufficient capacity to fill the receptacle at the desired rate.

As shown in Figs. 11 and 13, the valve casing 100 is provided with another by-pass around the valve 130, the purpose of this by-pass being to afford quick relief of the pressure against the left hand side of the diaphragm 153 (Fig. 3) at the conclusion of the pressure-tempering period. This by-pass comprises ports 170 and 172, and is normally closed by a spring-pressed check-valve 170 so arranged as to prevent the flow of water from the source of supply into the receptacle but to permit flow in the opposite direction sufficient for the purpose stated.

When the primary controlling valve 115 is returned to its initial position (Fig. 13) as hereinafter explained, to terminate the pressure-tempering period, its channel 117 connects the port 123 with the drain port 158. This connection not only drains the upper end of the cylinder 33 (Fig. 4) through pipe 101 but it also causes a quick drop of pressure against the left hand side of the diaphragm 153 (Fig. 3), since the check-valve 170 and the small by-pass 129 (Fig. 13) both permit water in the pipe 103 to flow back into the port 123 and thence through the draining channel 117. At this point the higher pressure in the receptacle 10 deflects the diaphragm 153 to the left, whereupon a small quantity of water in the receptacle is discharged through pipe 106, valve casing 105, pipe 161 and overflow drain 160.

As hereinbefore explained, the first movement

of the primary controlling valve 115 to the position represented in Figs. 4, 8, 9 and 10 initiates the operation of the hydraulic operating unit by which the closure 12 is applied to the receptacle and by which the members 14 are operated to supplement the closing force applied to the closure. This position of the primary controlling valve also directs water under pressure from the pump through the valve 130 (Fig. 9) and into the receptacle 10. In due course, the primary valve 115 will be returned automatically to its initial position as shown in Figs. 13 and 14 by automatic means including the spring 146 and either of two alternative controlling devices one of which is a timing device that governs the length of the pressure-tempering period.

As herein shown this timing device comprises a hydraulic dash-pot, the cylinder 50 of which contains oil and stands upright on the platform 1 (Figs. 1, 4 and 6), its lower head 51 being secured to the platform by screws 52. The piston 54 is affixed to the lower end of a tubular piston-rod 55 through which a regulating rod or stem 56 extends. The upper end of this inner rod is provided with a handle 57 (Figs. 1 and 4) by which it may be rotated to regulate the timing effect of the dash-pot. A pointer 61 formed on the handle 57 cooperates with a scale 60 carried by a member 58 secured to the upper end of the tubular piston-rod 55. The tubular rod 55 extends loosely through a bearing 67 in a spider 66 formed on the upper end of the piston, and in operation the tubular rod is capable of a short vertical movement relative to the piston whereby the lower end of the tubular rod is movable to and from a valve seat 65 surrounding a passageway 64 through the bottom of the piston. The extent of such relative movement may be regulated by a nut 68 screwed on and carried by the rod 55.

When the closure 12 is rising to the position shown in Fig. 4, the lug 156 (Fig. 1) projecting from one of the brackets 25 carried by the closure engages and lifts a weight 74 affixed to the rod 55. Under these conditions, the piston 54 (Fig. 6) is raised to the upper end of the cylinder 50 by the collar 68 on the lower end of the piston-rod 55, and the oil in the cylinder 50 may flow freely through the opening 64. On the other hand, when the closure 12 descends the weight 74 is deprived of the supporting effect of the lug 156, with the result that the rod 55 drops to its seat 65 on the piston (Fig. 6), thereby transferring the load of the weight to the piston and to the oil below the piston. The oil can now flow upwardly through the opening 64 only as rapidly as it may pass through a restricted passageway formed in part by the interior of the rod 55, in part by a face 71 of the regulating rod 56, and in part by a small port 70 extending radially through the rod 55 above the piston head. Under these conditions the descent of the piston is slow and may require several minutes. Turning the inner rod 56 relatively to the outer rod 55 regulates the rate of flow of the oil through this restricted passageway and thereby regulates the speed at which the piston may descend.

The piston-rod 55 also carries a collar 75 (Figs. 1, 2, 4 and 14) which, when the piston 54 is about to reach its lower limit of travel, depresses the lever 141, as shown in Fig. 14, and thereby disengages the latching finger 140 from the notch in the stud 138. The primary controlling valve is thus tripped and is returned to its initial position.

tion, whereupon the draining channel 117 in the primary controlling valve drains the upper end of the cylinder 33 (Fig. 4) and at the same time relieves the pressure on the left-hand side of the diaphragm 153 (Fig. 3).

Referring to Fig. 13, the channel 117 now permits the water above the piston 35 (Fig. 1) to return to the storage tank 90 through port 40, pipe 101 (Fig. 4), port 123 (Fig. 13), channel 117, port 158, port 162 (Fig. 8) and pipe 108 (Fig. 4). At the same time, the water from the pump releases the closure 12 from the treatment receptacle and raises the closure to its initial position, the operating connection to the lower 15 end of the cylinder 33 including supply pipe 96, port 122, channel 116, port 124 and pipe 125. As the closure 12 rises it returns the piston 54 of the timing device to its initial position at the upper end of the cylinder 50.

Instead of utilizing the timing device above described, the pressure-tempering period may be terminated by an alternative device of the type shown in Fig. 12. In this figure, the primary controlling valve is latched by the finger 140 and the stud 38 and stands in the same position as that represented in Figs. 4 and 10, but the tripping of the lever 141 is effected by the development of a certain pressure of the liquid in the receptacle 10 irrespective of the time factor. For this purpose, a pipe 180 forms communication between the interior of the receptacle and a chamber 181 in which a piston 182 is arranged. A stem 183 extends from the piston through a screw-threaded plug 186 and is arranged to operate the lever 141 to release the valve-restraining stud 138. A spring 184 surrounding the stem 183 bears against a head 185 at the lower end of the stem and thereby normally depresses the piston 182. The plug 186 may be screwed up or down to regulate the applied force of the spring 184 and thus determine the degree of fluid pressure required to release the primary controlling valve.

To insure filling the treatment receptacle 10 with water for tempering purposes after the closure 12 has been applied and tightly secured, the closure is provided with a venting device 110 (Figs. 1 and 2) through which all air initially in the receptacle may be expelled as water is pumped in. This venting device encloses a float valve 112 by which the vent is automatically closed by the water when all air has been expelled.

The closure 12 is utilized to carry the work into the treatment receptacle and to remove it therefrom. For this purpose, slides 152 on the bottom of the closure are arranged to receive supporting flanges at the top of a perforated container 150 in which the soles 151 are placed.

As shown in Fig. 1, a valved pipe 190 is connected to the bottom of the receptacle 10 to provide for completely draining and cleaning the receptacle when desired, but in the usual course of operation the liquid in the receptacle will never descend below the intermediate level indicated by a broken line in Fig. 5. However, the small quantity of water that is discharged from the receptacle through the pressure-operated draining valve shown in Fig. 3 after each pressure-tempering period will carry off some of the dirt and other foreign substances that may be brought into the receptacle by the work. It will be understood, moreover, that the supply of fresh or clean water available in the storage tank 90 will, in every case, counteract the partial dis-

charge through the drain pipe 161 and the overflow 160.

Having described our invention, what we claim as new and desire to secure by Letters Patent of the United States is:—

1. An apparatus for treating articles with liquid comprising a pressure-sustaining treatment receptacle, a removable closure therefor, a hydraulic operating unit by which said closure is carried to, clamped against, and retracted from the receptacle all by hydraulic pressure, a source of liquid under pressure, conduits through which liquid may be supplied from said source to said operating unit and to the receptacle, a valve movable manually to initiate a cycle of operations by directing liquid to said operating unit through one of said conduits, and fluid-controlled means thereafter operable automatically in consequence of closing movement of said closure to supply liquid from said source into the receptacle, to maintain the pressure of the liquid in the receptacle for a certain length of time, to release the pressure in the receptacle, and to retract said closure. 20

2. An apparatus for treating articles with liquid comprising a source of liquid under pressure, a pressure-sustaining treatment receptacle, a movable closure for said receptacle, means for tightening said closure against the receptacle, a hydraulic operating unit by which said tightening means and said closure are both operable to release the closure and retract it from the receptacle, conduits for supplying liquid from said source to said receptacle and to said unit, and automatic means by which communication is controlled between said source and said receptacle and between said source and said operating unit. 30

3. An apparatus for treating articles with liquid comprising a source of liquid under pressure, a pressure-sustaining treatment receptacle, a movable closure for said receptacle, means for tightening said closure against the receptacle, a hydraulic operating unit by which said closure and said tightening means are both operable to close the receptacle and fasten the closure, conduits for supplying liquid from said source to said receptacle and to said unit, valve means for controlling communication between said source and said receptacle and between said source and said operating unit, and automatic means for operating said valve means. 40

4. An apparatus for treating articles with liquid comprising a source of liquid under pressure, a pressure-sustaining treatment receptacle, a movable closure for said receptacle, means for tightening said closure against the receptacle, a hydraulic operating unit by which said tightening means and said closure are both operable to release the closure and retract it from the receptacle, conduits through which liquid may be supplied from said source to said receptacle and said operating unit, and automatic means for closing communication between said source and said receptacle and simultaneously establishing an operating connection between said operating unit and said source of liquid. 50

5. An apparatus for treating articles with liquid comprising a source of liquid under pressure, a pressure-sustaining treatment receptacle, a movable closure for said receptacle, a hydraulic operating unit by which such closure is operable to close and open the receptacle, conduits for supplying liquid from said source to said receptacle and to said unit, a valve operable manually to 60

- direct liquid from said source to said operating unit whereby closing movement is imparted to said closure, a valve normally closing communication between said source and said receptacle but operable by a certain pressure of the liquid on the supply side thereof to open such communication, and automatic means by which said manually operable valve is operated to close said communication and direct liquid from said source to said operating unit through a connection whereby said unit is operated to retract said closure from the receptacle.
6. An apparatus for treating articles with liquid comprising a pressure-sustaining treatment receptacle, a movable closure therefor, a double-acting hydraulic operating unit by which said closure is moved to and from the receptacle, a valve casing having a supply port, a draining port and two distributing ports, a conduit connecting said supply port with a source of liquid under pressure, distributing conduits connecting said distributing ports respectively with opposite ends of said operating unit, a valve having a supply channel arranged to connect said supply port alternatively with each of said distributing ports and also having a draining channel arranged to connect said drain port alternatively with each of said distributing ports, and a branch conduit connecting one of said distributing ports with the receptacle to supply liquid thereto and to drain liquid therefrom under control of said valve.
7. An apparatus as defined in claim 5 having a spring-closed check-valve in said branch conduit arranged to be opened by a certain pressure of liquid between it and the valve first mentioned.
8. An apparatus as defined in claim 5 having two check-valves in by-pass relation in said branch conduit, one arranged to supply liquid to the receptacle and the other to release liquid therefrom, and a spring arranged normally to close the supply check-valve while the liquid on the supply side thereof is flowing toward said operating unit.
9. An apparatus for treating articles with liquid comprising a pressure-sustaining treatment receptacle, a removable closure therefor, a hydraulic operating unit by which said closure is operated to close and open the receptacle, a primary controlling valve having a supply channel and a draining channel, means for supplying liquid under pressure to said supply channel, distributing conduits controlled alternatively by said supply channel and said draining channel, one of said conduits forming connections with the receptacle and one end of said operating unit and the other forming connection with the other end of said unit, and automatic timing means arranged to move said valve to a position in which said operating unit will be supplied with liquid to retract said closure from the receptacle.
10. An apparatus for treating articles with liquid comprising a pressure-sustaining treatment receptacle, a removable closure therefor, a hydraulic operating unit by which said closure is operated to close and open the receptacle, a primary controlling valve having a supply channel and a draining channel, means for supplying liquid under pressure to said supply channel, distributing conduits controlled alternatively by said supply channel and said draining channel, one of said conduits forming connections with the receptacle and one end of said operating unit and the other forming connection with the other end of said unit, and means operable by a certain pressure of the liquid in the receptacle to move said

valve to a position in which said operating unit will be supplied with liquid to retract said closure from the receptacle.

11. An apparatus for treating articles with liquid comprising a source of liquid under pressure, a pressure-sustaining treatment receptacle, a movable closure for said receptacle, a double-acting hydraulic cylinder the piston of which is operable in one direction to impart closing movement and in the opposite direction to impart opening movement to said closure, a two-way valve by which liquid from said source may be supplied to the ends of said cylinder alternatively, means for supplying liquid to the receptacle from a point between said valve and said cylinder, and automatic means including a timing device by which said valve is operated to cut off the receptacle and one end of said cylinder from said source and to direct the liquid from the latter to the opposite end of said cylinder.

12. An apparatus for treating articles with liquid comprising a pressure-sustaining treatment receptacle, a movable closure for said receptacle, a double-acting hydraulic cylinder the piston of which is operable in one direction to impart closing movement and in the opposite direction to impart opening movement to said closure, a source of liquid under pressure, valve means and distributing conduits arranged to supply liquid from said source into one end of said cylinder and to drain the opposite end thereof, and vice versa, and means including a normally closed valve arranged to supply liquid from said source to the receptacle, said normally closed valve being arranged to be opened by a higher pressure of the liquid acting against the closing side of said piston than that developed while the piston is moving in the direction first specified.

13. An apparatus for treating articles with liquid comprising a source of liquid under pressure, a treatment receptacle, a removable closure for said receptacle, hydraulic means operable by liquid from said source to retract said closure from the receptacle, a timing device, automatic valve means controlled by said timing device to supply liquid from said source to operate said hydraulic means, and means operable by said hydraulic means to restore said timing device to its initial position.

14. An apparatus for treating articles with liquid comprising a source of liquid under pressure, a treatment receptacle, a removable closure for said receptacle, hydraulic means operable by liquid from said source to retract said closure from the receptacle, a fluid-controlled timing device, automatic valve means controlled by said timing device to supply liquid from said source to operate said hydraulic means, and means operable by said hydraulic means to restore said timing device to its initial position.

15. An apparatus for treating articles with liquid comprising a source of liquid under pressure, a treatment receptacle, a removable closure for said receptacle, hydraulic means operable by liquid from said source to retract said closure from the receptacle, a timing device arranged to be set in operation by closing movement of said closure, and automatic means controlled by said timing device to establish an operating connection between said source and said hydraulic means whereby the latter is caused to retract the closure.

16. An apparatus for treating articles with liquid comprising a source of liquid under pressure, a treatment receptacle, a removable closure for

said receptacle, hydraulic means operable by liquid from said source to impart closing movement to said closure, primary valve means for controlling the flow of liquid from said source to said hydraulic means, and a normally closed valve arranged to be opened by a certain pressure of the liquid exerting closing force on said hy-

draulic means whereby some of said liquid is supplied to the receptacle to treat the work therein.
